UNITED STATES PATENT OFFICE.

HARRY ETHERIDGE, OF ZELIENOPLE, PENNSYLVANIA.

RAILWAY-RAIL SUPPORT.

Application filed June 12, 1925. Serial No. 36,619.

One feature of my invention relates to the class of rail supports which carry but one of the parallel track rails but do not span the track as do cross-ties.

Where such rail supports as now constructed are employed, the tendency is for passing traffic to tip the support inwardly toward the axis of the track and thus impart a lateral rolling action to the support, which 10 in time loosens it in the ballast or road bed so that the rail is no longer firmly supported.

To overcome this difficulty I have invented a new and improved rail-support 15 which has a more extended bearing surface on the inner side of the rail than on the outer side, the inside bearing surface being extended towards the axis of the track sufficiently to overcome the tendency to tip or 20 roll.

The preferred embodiment of my invention, shown herein, is a substantial T-shaped support, horizontally disposed, and the head of the T supporting the rail from beneath 25 while the stem of the T extends inwardly towards the axis of the track, and the upper surface of the stem being preferably depressed so that the stem is embedded in the ballast.

My improved rail support is preferably 30 formed of concrete or similar material, having embedded therein metallic reinforcement, and I have provided a new and improved character of such reinforcement.

Another feature of my invention is the 35 provision of new and improved means of fastening the rail to a rail-support, and I provide internally threaded sleeves which are embedded in the material of the support, 40 with their upper ends exposed, and which are welded or otherwise attached to the internal reinforcement of the rail support.

In the accompanying drawings, wherein 45 I illustrate a practical embodiment of my invention, Fig. 1 is a plan view showing a rail mounted on one of my supports; Fig. 2 is a plan view of the support with the rail removed and the reinforcement being shown in dotted line; Fig. 3 is an end view of the 50 support, the material being partially broken away to show the reinforcement; Fig. 4 is a plan view of the reinforcement before it is embedded in the material of the support; Fig. 5 is a front view of the same; Fig. 6 is 55 an enlarged detail of the portion of the reinforcement showing the method of an-

choring the rail fastening means thereto; Fig. 7 is a plan view of the same; Fig. 8 is a view similar to Fig. 1 showing the form of my improved support used under a rail 60 joint, and Fig. 9 is a view showing the arrangement of the rail supports for the parallel rails of a railway track.

Referring first to Figs. 1 to 7 inclusive, A represents the rail-support, and B the 65 rail carried thereby. It will be noted that a more extended bearing surface on the road bed is provided for the support on one side of the rail than on the other, and the more extended bearing surface is positioned on the 70 inner side of the rail, or toward the axis of the railway track.

Thus, in the preferred form of my rail-support, which is shown in the drawings, the same is substantially T-shaped, the arm 1 75 supporting the rail from beneath and extending parallel therewith, while the stem 2, of narrower width than the length of the arm 1, extends inwardly towards the axis of the track. The arm and stem of the T are 80 preferably integral and formed of concrete which is suitably reinforced, as will hereafter be explained.

The arm 1 of the support is of sufficient thickness to hold the rail at the proper elevation and is preferably provided with a longitudinally disposed and sunken recess 3 in which is stepped a resilient mat 4, such as of rubber or other resilient or compressible material, upon which the rail rests, and 90 which will at all times support the rail out of contact with the support A. The stem 2 of the support has its top surface at lower level than the top surface of the arm 1, as shown in Fig. 3, so that it may be embedded 95 in the ballast, which latter is preferably continued over the top of the stem 2.

In Fig. 4 I show the character of reinforcement which I prefer to use. The same 100 consists of the substantial oblong frame 5 formed of flat metal bar placed on the edge, and of proper dimension to be embedded in the material of that portion of the support which forms the arm 1, as shown in Fig. 2. The stem 2 is reinforced by means of a nose 105 frame 6 formed by bending up a strip of similar material into proper shape to reinforce the stem of the support, as shown in Fig. 2, the rear ends of the bar being curved outwardly and welded or riveted to the frame 5 as at 7. I also prefer to employ 110 transverse members which brace the frame

and better anchor it in the material of the support. Thus 8 and 9 are bars, preferably round bars, laid on the top of the frame with their ends welded as at 10, while 11 and 12 are similar bars, but laid in opposite direction with their ends welded to the under edge of the frame.

13 are internally threaded metal sleeves which are welded in vertically disposed positions to the end members of the frame 5 and have their lower ends preferably closed by the screw plugs 14. These sleeves are so disposed that their upper ends are exposed at the top of the stem 2 of the support at either 15 side of the sunken seat 3 and near the opposite ends of the same. Thus the sleeves receive the screw bolts or other fastening means which are employed to attach the rail to the support, such fastening means not 20 being shown.

It will be noted that the frame 6 is preferably tilted downwardly and toward the axis of the track so that its upper surface will not approach too near the upper surface 25 of the stem 2.

In Fig. 8 I show the support A' which differs only from the support A, Fig. 1, in that the arm 1 of the former is extended, thus providing a longer bearing surface, so 30 that it may support the joint between the two abutting rails B' and B². Thus A is intended for a rail-joint support.

The rails are supported at proper intervals by the supports A, and at the joints between abutting rails by the supports A', the stem 2 of said supports extending inwardly towards the axis of the track but being preferably entirely unconnected with the supports of the parallel rail.

45 The top edge of the arm 1 of the support is preferably beveled as shown at 15 so that the ballast may be packed about the support and substantially to the top surface of the same, thereby improving the anchorage of the support in the ballast. Likewise the top, front and side edges of the stem 2 are similarly beveled, thereby obtaining a better anchorage in the ballast.

50 The corners between the stem 2 and arm 1 are rounded by the provision of the fillets 16, thus adding strength.

By the use of my improved support which is provided with a more extending bearing surface on the road bed towards the axis 55 of the track, I am enabled to entirely overcome the tendency of the support to rock or

tip inwardly, and therefore there is no loosening of the support in the road bed by passing traffic. The development of my support into a substantial T shape also materially aids in attaining a firmer and more permanent positioning of the support in the road bed.

What I desire to claim is:—

1. In a railway track structure, individual rail supports for the opposite rails of the track, said supports being unconnected with each other and being of substantially T-shape with the head of the T disposed longitudinally beneath the rail and the stem 70 of the T extending inwardly toward the axis of the track, the top surface of the stem of the T being at a lower level so as to be sunk in the ballast, for the purpose described.

2. In a railway track structure, individual rail supports for the opposite rails of the track, said supports being unconnected with each other and being formed of reinforced concrete and of substantially T-shape with the head of the T disposed longitudinally beneath the rail and the stem of the T extending inwardly toward the axis of the track, the top edges of the support being bevelled to obtain a letter bedding in the 80 ballast, for the purpose described.

3. In a railway track structure, individual rail supports for the opposite rails of the track, said supports being unconnected with each other and being of substantially 90 T-shape with the head of the T disposed longitudinally beneath the rail and the stem of the T extending inwardly toward the axis of the track, the top surface of the stem of the T being at a lower level so as to be 95 sunk in the ballast, and the top edges of the support being bevelled to obtain a better bedding in the ballast, for the purpose described.

4. An individual rail support for railway 100 rails, comprising a reinforced concrete block of substantially T-shape, the top of the T being disposed longitudinally of the rail while the stem of the T extends inwardly toward the axis of the track, and said support having embedded therein metal bars assembled to form a frame of a shape corresponding to that of the support but of less dimensions.

Signed at Pittsburgh Pa. this 10th day of 110 June 1925.

HARRY ETHERIDGE.
